Attorney

UNITED STATES PATENT OFFICE.

EMILIO CORTÉS, OF MEXICO, MEXICO.

CRUDE-OIL ELEVATOR.

Application filed November 20, 1923. Serial No. 675,967.

To all whom it may concern:

Be it known that I, EMILIO CORTÉS, citizen of the United Mexican States, residing at Mexico city, Mexico, have invented certain new and useful Improvements in Crude-Oil Elevators, of which the following is a specification.

This invention relates to an elevator for raising crude oil at atmospheric temperature out of tanks. The adhesiveness of the crude oil is taken advantage of by conducting the endless belt of the elevator through the oil and against an adjustable scraper extending into a gutter for collecting the oil adhering to the belt.

The endless belt is trained over two pulleys one of which is adjustably mounted in a bearing and the other permanently mounted in a bearing, both bearings being fixed to a swinging frame resting on top of a horizontal frame.

The object of the invention is to extract crude oil from deposits or tanks without necessitating the use of a pump or the heating of the crude oil.

Fig. 1 is a side view of the elevator.

Fig. 2 is an end view of same.

On the top of tank (1) is mounted a horizontal frame of I-beams (2) for the general support of the elevator. Near one end of the tank an axle (3), fastened transversely to the elevator frame (4) also made of I-beams, may turn in the bearings (5).

Two diagonal struts (6), pivoted to clamps (7) sliding on the frames (4) and (2), keep the frame (4) adjusted with relation to the horizontal frame (2) according to the inclination required for the elevator.

At one end of elevator frame (4), the driving shaft (8) mounted in the bearings (9) supports a transmission pulley (10) and the upper elevator pulley (11), over which latter passes the endless belt (12) as also over the lower elevator pulley (13), the shaft (14) of which is adjusted by two stretcher rods (16) in the elongated loop bearings (15) attached to the other end of frame (4).

A tray (17) fastened to the hangers (18) is suspended from brackets (19) while the lower ends of the hangers are forced toward the elevator belt by the action of spiral springs (20) on brackets (21).

The tray extends into a gutter or pipe (22) by which the crude oil is discharged.

As the elevator belt should be driven at slow speed a reducing belt system (23) trans-

mits motion from the motor (24) to the pulley (10).

The elevator belt may of course be made of leather, metal or any other flexible material or may be substituted by a chain.

The pulleys over which the elevator belt passes may be large, or substituted by two smaller pulleys at the bottom of tank (1) in order to enlarge and lower the extension of the belt, which must be submerged in the crude oil. This may be advisable in order to enable the extraction of the oil from the tank when the latter is almost empty.

It is of course understood that the crude oil adhering to the belt is scraped off due to the resistance of the tray edge being held against the moving belt, and is thus collected in the tray.

Having thus described my invention what I claim is:

1. A crude oil elevator comprising a swinging frame, pulleys in each end thereof, an endless belt trained over said pulleys, stretching means for said belt, means for adjusting said frame at an inclination, a scraper tray yieldingly held against the endless belt, and means for driving said belt at slow speed.

2. A crude oil elevator, comprising a tiltable frame; an endless belt mounted therein; means for retaining said frame in adjusted tilted position; means for driving said belt; and means for removing from said belt the oil adhering thereto.

3. A crude oil elevator, comprising a tiltable frame; an endless belt mounted therein; a supporting frame with which the tiltable frame is pivotally connected; retaining members pivotally related at opposite ends to the tiltable and supporting frames to hold the former in adjusted tilted position; means for driving said belt; and means for removing from said belt the oil adhering thereto.

4. A crude oil elevator, comprising a supporting frame; a pair of alining bearings mounted thereon; a tiltable frame; an endless belt mounted in the latter frame; a horizontal axle secured intermediate its ends to the tiltable frame and journaled at its ends in said bearings, thereby to enable a swinging movement of the tiltable frame in a vertical plane; means for retaining said tiltable frame in adjusted tilted position; means for driving said belt; and means for removing from said belt the oil adhering thereto.

5. A crude oil elevator, comprising a sup-

porting frame and a tilttable frame each consisting of a pair of spaced, parallel beams; an endless belt mounted in the tilttable frame; a pair of clamps slidably mounted 5 on the beams of each frame; a pair of diagonal struts pivotally connected at opposite ends to said pairs of clamps to retain the tilttable frame in adjusted tilted position; means for driving said belt; and means for 10 removing from said belt the oil adhering thereto.

6. A crude oil elevator, comprising a supporting frame and a tilttable frame each consisting of a pair of spaced, parallel beams; 15 an endless belt mounted in the tilttable frame; a pair of alining bearings mounted on the beams of the supporting frame; a horizontal axle secured intermediate its ends to the beams of the tilttable frame and journaled at its ends in said bearings, thereby to enable a swinging movement of said tilttable frame in a vertical plane; a pair of clamps slidably mounted on the beams of each frame; a pair of diagonal struts pivotally 20 connected at opposite ends to said pairs of clamps to retain the tilttable frame in adjusted tilted position; means for driving said belt; and means for removing from said belt the oil adhering thereto.

7. A crude oil elevator, comprising a vertical frame embodying a pair of spaced, longitudinal beams; an endless belt mounted 25

therein; supporting means for said frame; means for driving said belt; a pair of brackets attached to the upper portions of said beams; a pair of depending hangers pivoted to said brackets; a scraper disposed between and connected to said hangers to remove from the belt the oil adhering thereto; a pair of brackets attached to said beams below the first-named brackets and with which the lower ends of the hangers are loosely engaged; and springs mounted on the lower brackets and bearing against said lower hanger ends to force the scraper yieldingly 40 against the belt.

8. A crude oil elevator, comprising a vertical frame embodying a pair of spaced, longitudinal beams; upper and lower pairs of bearings attached to said beams; the lower 50 bearings being elongated; upper and lower pulley shafts mounted in said bearings, a pulley on each shaft; an endless belt passing around said pulleys; driving means connected to the upper shaft; a pair of adjustable stretcher rods connected intermediate their ends to said beams and at their lower ends to the lower pulley shaft, to move the latter and its pulley upward or downward to adjust the tension of the belt; and a scraper 55 for removing from the upper portion of said belt the oil adhering thereto.

In testimony whereof I affix my signature.

EMILIO CORTÉS.
